Application March 6, 1942, Serial No. 433,684

7 Claims. (Cl. 62—108.5)

The invention relates to refrigerating apparatus generally, and more particularly to an improvement in combined ice cube freezing trays and ice cube ejector mechanisms, especially designed for use with refrigerating machines having freezing chambers of a capacity to supply ice in cube form for both commercial and household purposes.

The prior related art evidences that many attempts have been made to provide ice cube freezing trays alone, or combined with ice cube ejector mechanisms, to permit of quick freezing of water contained in the several ice cube forming compartments of a freezing tray and, at the same time, allow for convenience and ease in removal of trays from the freezing chamber of a refrigerating machine, as well as to facilitate the dislodgement of ice cubes from the tray compartments. Among these various attempts, trays of metal, while permitting of quick freezing, failed to allow for desired convenience and ease of removal of the trays themselves from the freezing chamber nor the frozen cubes from the tray compartments by reason of the maximum degree of adhesion occurring between the ice formations and the metal and, to accomplish this, heat applications were more often than not resorted to. Trays of rubber have had some degree of success in this connection, particularly in the elimination of heat applications to break down the effects of adhesion, the ice cubes here being dislodged from the several ice cube forming compartments by flexing the walls of a tray. These rubber trays, however, have disadvantages, first, if the cubes are hard frozen, there is a disconcerting adhesion of the ice cubes to the walls of the cube forming compartments, and, second, by reason of the low conductivity of rubber, excessive expenditures in time and power, and consequently in cost, being required to freeze an equal volume of ice as compared to that when ordinary metal trays are employed. Also, in the use of rubber trays, the ice formation begins initially at the top surface of the water in the tray compartments, as distinguished from the initial freezing of the water at the sides and bottom of metal trays, the top surface of the water in the first instance freezing substantially flat and the final freezing occurring at the bottoms of the compartments with a tendency to bulge downwardly, while, with metal trays, the bulge occurs at the top surfaces of the formed cubes. Again, certain trays have been made from a combination of metal and rubber, or of metal alone, coupled with ice cube ejector devices and

mechanisms, but few of these have functioned with that degree of success to make them commercially practical, their inefficiency being due to various causes, particularly to the adhesion of the ice cubes to the tray compartment walls sufficiently to prevent ready dislodgement and removal and to the frosting over and sticking of the operative parts.

The present invention has for its primary object the provision of a combined ice cube freezing tray and mechanical ejector mechanism that surmounts these objectionable features and disadvantages of many of the exemplified structures disclosed in the prior art, with due consideration to simplicity in design and operation, as well as to comparatively low cost in manufacture.

Another object of the invention resides in the provision of a compartmented tray construction that is made entirely from any suitable non-metallic material that can be molded or pressed to required form, such as, for instance, the synthetic thermoplastic material known as "Koroseal" which can be worked to desired form, it having been found to be superior to natural rubber in that it is practically tasteless and odorless, that substantially no adhesion occurs between the surfaces of the ice cubes and the opposed walls of the compartments of trays made from it, and that, by reason of a higher conductivity, the time required for freezing the water content of the tray compartments and, consequently, the amount of power for refrigerating machine operation, is reduced to a degree comparable to that when metal freezing trays are used.

Another object of the invention has to do with the provision of a main, substantially rigid, tray structure to support cube forming compartmented tray sections which are made from a lighter weight of the aforesaid material, in combination with a frozen cube ejector mechanism, wherein, upon manipulation of the mechanism, certain of the compartments of one or the other of the sectional trays will be acted upon to detach themselves from contact with the opposed surfaces of the frozen cubes concurrently with movements of dislodgement or lift of the latter under the impetus of the mechanism, the cubes being projected upwardly of the compartments upon completion of the operative movement of the mechanism for subsequent removal and use.

With the foregoing and other objects and advantages of equal importance in view, the invention resides in the certain new and useful combination, construction, and arrangement of parts, as will be hereinafter more fully described,

set forth in the appended claims, and illustrated in the accompanying drawing, in which:

Figure 1 is a fragmentary top plan view of the improved ice cube freezing tray, with portions broken away to show certain of the features of tray and ejector mechanism construction;

Figure 2 is an end elevation of the tray unit as it appears in supported position within a freezing chamber of a refrigerating machine, a portion of the end wall being broken away to show certain other features of tray and ejector mechanism construction; and,

Figure 3 is a longitudinal vertical section taken on the line 3-3 of Figure 1.

Referring to the drawing, wherein like characters of reference denote corresponding parts throughout the several views, the invention as is exemplified therein is embodied in a main open-topped tray 10 of substantially pan-like configuration and standard dimensions to replace the ordinary cellular type of ice cube freezing tray which is in the nature of a sliding drawer for its removal from and replacement within the freezing chamber of a refrigerating machine, for instance, the freezing chamber A which has its interior provided with suitable supports, such as the oppositely arranged angled brackets or rails B.

The main tray 10, as before stated, is preferably made from a non-metallic material, such as "Koroseal," or the like, and has its interior divided, for instance, into four main compartments by medially disposed longitudinal and transverse division walls 13 and 14 which, with the bottom wall 11 and the end walls 12, are made to a somewhat greater thickness than that of the side walls 15, in order to impart substantial strength and rigidity to the tray structure. The side walls 15 are slightly inclined in an outward direction, while the inner surfaces of the end walls 12 and the division walls 13 and 14 are similarly inclined to give a uniform downward slope to these opposed walls of said main compartments, substantially as shown and for purposes which will hereinafter be explained.

Removably seated within each front and rear half portion of the main tray 10 is a multi-compartment, ice cube forming, tray section 16 which is molded or pressed from a lighter weight of the same material from which the main tray 10 is fabricated. Each of the tray sections 16 has its end and outer side walls 17 and 18 inclined to conform to the inclination of the end and outer side walls 12 and 15 of the main tray 10, and is provided with a medially disposed longitudinal partition structure 20 extending between its end walls 17 to divide the interior of the tray section into two elongated compartmented portions corresponding to the said main compartments of the main tray. This partition 20 is formed of spaced walls pressed upwardly from the bottom of each tray section 16 and a horizontal portion connecting said walls at their top edges. The space between the partition walls opens downwardly through the bottom of the tray section 16 for seated engagement with the corresponding portion of the longitudinal division 13 of the main tray 10, the partition walls being oppositely inclined to conform to the inclination of the opposite surfaces of the division wall 13. The top edges of the end and side walls 17 and 18 of each tray section 16 are formed with outwardly angled flanges 19 which rest upon the edges of the corresponding end, transverse di-

vision, and side walls 12, 14, and 15, respectively, of the main tray 10. Each elongated half section of each of the tray sections 16 is divided into a plurality of individual ice cube forming pockets, five of the same being shown by way of example, by uniformly spaced, transversely extending, partition walls 21. Thus, each of the tray sections 16 have a capacity of ten ice cubes and the whole freezing unit a capacity of twenty cubes. The transverse partition walls 21 are vertically disposed and are made to the same thickness of the material forming the whole of the sectional trays 16. By outwardly inclining the opposite end walls of the several ice cube forming pockets and similarly shaping the outer side walls of the pockets at the opposite ends of each sectional row thereof, the dislodgement and removal of frozen cubes is facilitated to an extent that will presently be explained.

Formed in the bottom wall 11, along the longitudinal center of each quarter section or main compartment of the supporting tray 10, is a slotted opening 22 which extends the entire length of the compartment section between the end and transverse division walls 12 and 14. Disposed within each of the slotted openings 22, parallel thereto, is a rocker shaft 23 that has its opposite ends journaled in the end and transverse division walls 12 and 14, the said walls being suitably apertured to receive trunnion-like extensions 24 at the shaft ends. If necessary or advisable, these apertures may be bushed with metal in any usual manner determined upon by the artisan, so as to provide a metal to metal bearing between the bushings (not shown) and the trunnions 24.

As shown, each of the rocker shaft sections 23, between the supporting trunnions 24, is made with a continuously elongated cam surface 25 which bears eccentric relation with respect to the points of support of the shaft ends in the aforesaid bearing apertures. The trunnions 24, at the outer ends of the shaft sections 23, are made slightly longer than those at the inner ends of the shafts and these extended portions 26 are shaped, as by being squared, for the engagement therewith of a suitable actuator, such as the hand-crank 27; the squared ends 26 being accessible for the application of the operating handle 27 thereto at the bearing apertures opening through the opposite end walls 12 of the main tray 10.

Resting upon the bottom of each main compartment of the main tray 10 is a flat metal strip or plate 28 having a length and a width to fully overlie and close the slotted opening 22 and the dual function of preventing any bulging of the overlying bottom walls of the individual ice cube forming pockets of a tray section 16 downwardly of a slotted opening 22 under the expansion effects of the freezing process, and, as a follower, to uniformly distribute the lifting force of the associated shaft section 23 to substantial areas of the overlying bottoms of the pockets and through these to the bottoms of the frozen cubes C for the dislodgement and lifting of the latter from within the pockets. As best shown in Figure 2, the follower 28 engages in depressions or channels 30 which are naturally formed in the bottom walls of the pockets and, consequently, in the bottoms of the frozen cubes themselves, due to the downward pressures of expansion during the freezing process. The followers 28 are thus held against lateral displacement from their cooperative relation with respect to the rocker

shafts 23 during the lifting operations. In order to prevent any abrasion of or other undue wear on the bottom walls of the pockets by the followers 28 during the lifting operations, the opposite longitudinal edges thereof are rounded off, as at 29.

In order to install the shaft sections 23, a trunnion 24, together with a squared extension 26, is made separate from the outer end of each section, and as a unit with a screw-threaded extension 31 projecting from the end of the trunnion opposite the squared extension, so that, with a shaft section 23 positioned within a slotted opening 22, securement of the trunnion is to be effected by the insertion of the screw-threaded extension 31 inwardly of the proper bearing aperture in an end of the main tray 10 and into tightened engagement with a complementally screw-threaded bore formed in the shaft end.

In the use of the ice cube freezing unit thus provided, all of the several pockets of the tray sections 16 will be filled with water in a usual manner and the unit inserted into the freezing chamber A. Upon completion of the freezing process, and it is desired to make use of some or all of the frozen cubes C, the tray unit 10 will be withdrawn from the freezing chamber, either entirely or partially as required. By withdrawing the tray unit outwardly to slightly more than one-half of its length, access may be had to the frozen cubes C in the first of the cube forming tray sections 16, when they may be easily dislodged and elevated successively from each of the two, right and left hand, rows of pockets by applying the hand-crank 27 to first one and then the other of the squared extensions 26 of the rocker shafts 23. A quarter turn of the hand-crank 27 and consequently of a shaft section 23 causes the cam surface 25 to exert an upward force against the associated follower plate 28. As the follower plate 28 is forced upwardly, its initial lift causes the bottom portions of the frozen cubes C, which bulge downwardly at opposite sides of the follower plate, to immediately separate from the underlying portions of the bottom walls and the lower connected portions of the end and side walls of the pockets. When the follower plate 28 has been elevated to the high point of the cam surface 25, each of the frozen cubes C in the particular pockets will be completely loosened from the several walls thereof and projected sufficiently above the top of the tray section 16 for ease in removal, substantially as is shown in Figure 2. With the frozen cubes C removed from the first of the tray sections 16, access to those in the other of the tray sections is to be had by reversing the tray unit 10, end for end, when the ejector operation will be repeated, as in the first instance. While it has been stated that the tray unit 10 can be left partially housed within the freezing chamber A during the removal of frozen cubes C from each of the tray sections 16, it will of course be understood that the tray unit 10 may be entirely removed from the freezing chamber A for the manipulation of the rocker shafts 23 and the subsequent removal of the frozen cubes C at the will of the user. However, by so removing the tray unit 10 from the freezing chamber A, it may be placed in inverted state over an open container (not shown) for the ejection of the frozen cubes C directly therein from the pockets of the tray sections 16, upon successive manipulations of the rocker shafts 23. It has been ascertained that, due to the absence of any appreciable adhesion existing

between the opposed surfaces of the walls of the cube forming pockets and the frozen cubes C, the tray sections 16 will remain undisturbed in their seated positions within the main tray 10 during operations for the ejection of the ice cubes, except for the illustrated distortion of the lower portions of the pockets, but otherwise they are subject to removal from the tray unit for cleaning and like purposes as required. By flaring the inner surfaces of the end walls 12 and the opposed surfaces of the transverse division wall 14 of the main tray 10, there is an almost instant release of the pressure of expansion between the opposed transverse sides of the immediate cube formations and the corresponding walls of the pockets upon the initial lifting movement of a shaft section 23. This cube freeing action is likewise facilitated by the similar flare of the side walls 15 and the opposed surfaces of the longitudinal division wall 13 of the main tray 10, as will be apparent.

Having thus fully described our invention, it is to be understood that the disclosed embodiment thereof is subject to such modification, i. e., changes in form and details of construction and arrangement of parts, that may fall within the scope of the claims appended hereto.

What is claimed is:

1. A freezing tray unit for refrigerating machines comprising a substantially rigid main tray having its interior quartered by medially disposed longitudinal and transverse partitions to provide four compartments of equal area, and a flexible tray supported upon each half portion of the main tray at opposite sides of said transverse partition and formed to provide parallel groups of ice cube forming pockets each occupying a corresponding compartment of the main tray, said trays being formed of a thermoplastic material to the surfaces of which a contained substance will not adhere when hard frozen, in combination with a means carried by the main tray in association with each of its compartments for independent cooperation with the bottoms of the corresponding group of pockets to dislodge the frozen ice cubes therefrom.

2. The tray unit as in claim 1, with each of the said means comprising a manually operable rocker shaft housed within a slotted opening in the bottom wall of the main tray and extending lengthwise of a compartment beneath the bottoms of the group of pockets seated therein.

3. The tray unit as in claim 1, with each of the said means comprising a manually operable cam shaft housed within a slotted opening in the bottom wall of the main tray and extending lengthwise of a compartment beneath the bottoms of the group of pockets seated therein, and a follower plate positioned within said compartment to normally close the slotted opening and adapted to distribute the lifting force of the cam shaft uniformly over portions of the bottoms of said pockets.

4. A freezing tray unit for refrigerating machines comprising a substantially rigid main tray having its interior divided into parallel elongated compartments, and a flexible tray seated upon the main tray and having rows of cube forming pockets depending into respective compartments of the main tray, in combination with a manually operable cam shaft housed within a slotted opening in the bottom wall of each compartment of the main tray, and a follower plate positioned within each compartment of the main tray to normally close the opening and to distribute the

lifting force of the cam shaft uniformly over portions of the bottoms of a respective row of said pockets.

5. A freezing tray unit for refrigerating machines comprising a substantially rigid main tray having its interior quartered by medially disposed longitudinal and transverse partitions to provide four compartments of equal area, and a flexible tray seated upon each half portion of the main tray at opposite sides of said transverse partition and formed to provide parallel groups of cube forming pockets, each group occupying a corresponding compartment of the main tray, in combination with a manually operable cam shaft housed within a slotted opening in the bottom wall of each compartment of the main tray, and a follower plate positioned within each compartment of the main tray to normally close said opening and to distribute the lifting force of the cam shaft uniformly over portions of the bottoms of the respective group of said pockets.

6. A freezing tray unit comprising a substantially rigid main tray, a flexible tray seated within the main tray, said main and flexible trays being formed of a non-metallic material to the surfaces of which a substance, contained within the flexible tray, will not adhere when frozen, an

eccentric member mounted for operative movements within a slotted opening extending lengthwise of the bottom wall of the main tray, and a follower positioned within the main tray to normally close said opening and to distribute the lifting force of said member uniformly over a portion of the bottom wall of the flexible tray for the ejection of a frozen content of the flexible tray therefrom.

7. A freezing tray unit comprising a substantially rigid compartmented main tray, a similarly compartmented flexible tray seated within the main tray, said main and flexible trays being formed of a synthetic material to the surfaces of which a substance, contained within the flexible tray, will not adhere when frozen, a cranked shaft mounted for operative movements within a slotted opening extending lengthwise of the bottom wall of each compartment of the main tray, and a follower positioned within each main tray compartment to normally close said opening and to distribute the lifting force of said shaft uniformly over a portion of the bottom wall of a respective compartment of the flexible tray for the ejection of a frozen content therefrom.
